UNITED STATES PATENT OFFICE.

HERBERT ELROY GORDON, OF SEATTLE, WASHINGTON.

RAKER-GAGE.

1,165,166.

Specification of Letters Patent. Patented Dec. 21, 1915.

Application filed October 7, 1913. Serial No. 793,846.

To all whom it may concern:

Be it known that I, HERBERT ELROY GORDON, a citizen of the United States, and a resident of Seattle, in the county of King and State of Washington, have invented an Improvement in Raker-Gages, of which the following is a specification.

My present invention relates to combined saw tools and more particularly to devices for use in connection with the sharpening and swaging of saw teeth, and my object is to provide a device of this character having a novel and highly effective gage clip for use in connection with the sharpening operation and a novel and highly useful gage for use in connection with the swaging operation, all of which parts are combined in a single device which may be readily manipulated and accurately adjusted and which permits of an unobstructed view at all times of the work being done.

In the accompanying drawing which illustrates my invention, Figure 1, is a side elevation of my improved device. Fig. 2, is a central vertical transverse section taken therethrough. Fig. 3, is another vertical transverse section, taken substantially on line 3—3 of Fig. 1. Fig. 4, is a top plan view of the intermediate portion of the device, and, Fig. 5, is a side elevation of the lower central portion of the device looking from the opposite side as compared to Fig. 1, and illustrating the swaging means.

Referring now to these figures, A represents the frame, body or block of my improved tool, which is provided with central cut out portions a and a' at its upper and lower edges respectively and which is provided at its upper and lower edges upon opposite sides of the cut out portions with laterally projecting lugs a^2 , to which lugs are secured longitudinal strips B and C, upon the upper and lower edges of the body frame or block A respectively and upon opposite sides of the cut out portions a and a' .

It will be noted that the strips B and C are secured in such manner that they may be readily removed either for repair or substitution, by means of a plurality of small screws or the like extending into the lugs a^2 . It is to be noted also that the strips B and C are laterally extended from relatively opposite side faces of the body, frame or block A and that the latter is provided with intermediate longitudinal ribs a^3 upon opposite sides to form guides for the purpose of spac-

ing the saw blade the selected distance from the frame or block A during either the trimming or swaging operations.

Vertically slidably mounted upon one face of the body, frame or block A, with its upper lateral flange d having its ends beneath the inner portions of the upper edge strip B, is a gage clip D, the lower rounded portion of which is engaged by a flat spring E, the ends of which bear upon lugs a^4 of the body, frame or block A, the spring tending to force the gage clip vertically and maintain its upper flange d tightly against the lower ends of set screws D' adjustably threaded through the inner portions of the strip B before mentioned, the said upper flange d of the gage clip having a longitudinal slot d' to receive the raker teeth of a saw blade F there-through, thus forming a gage for use in the operation of sharpening the saw teeth.

The gage clip D is guided in its vertical movement and adapted to be locked in adjusted position by means of a set screw G which works in a vertical slot d^2 of the gage clip and is threaded through the body frame or block A for this purpose, its head bearing upon portions of the gage clip upon opposite sides of the slot d^2 . Above its slot d^2 the gage clip is also provided with an outstanding lug d^3 vertically through which is threaded a clamping screw H, adapted to engage and clamp a jointing file between the same and the lower surface of the flange d , such as shown in Fig. 2, the jointing file being shown in dotted lines and indicated at I. The other gage is disposed upon the opposite side of the body, frame or block A and consists of a flat tempered spring J secured for the major portion of its length along one part of the lower strip C, this spring having an inner free end projecting within the space between the inner ends of strips C and there being an adjusting screw J' threaded through the strip C to bear upwardly against the free end of spring J for the purpose of forcing the latter inwardly to the desired extent in order to indicate the proper height of the raker teeth swaged by means of a hammer or other tool. From this it is believed to be apparent that, due to the particular construction and relation of the parts, an overhang is provided at the inner end of one of the portions of the strip C, that portion to which the gage spring J is secured, due to which the adjusting screw J' may, by threading

through the said overhanging portion of the strip, engage the gage spring J at a point much nearer the inner free end of this gage spring than would otherwise be possible, or 5 is possible with devices of this character now in use. The effectiveness of the device used as a gage is, by the above means, materially increased. Thus it will be seen that both the gaging clip and the gage 10 spring are capable of quick and accurate adjustment and permit of an unobstructed view at all times of the work being done, it being also apparent that both devices may be readily removed from the body frame or 15 block A either for repair or substitution.

I claim:—

In a device of the character described, the combination of a body plate provided with a central cut out portion in one edge and 20 having a laterally projecting bearing strip

portions of which extend along its said edge upon opposite sides of its said cut-out portion, one of said portions of said strip having its inner extremity extending into the cut-out portion to form an overhang, a gage 25 consisting of a flat spring secured along said latter portion of the said bearing strip and having a free inner flat end within the said cutout portion of the body plate, extending beyond the overhang of the bearing strip, 30 and an adjusting screw threaded through the said overhanging portion of the bearing strip and bearing inwardly against the free end of the spring, all for the purpose described.

HERBERT ELROY GORDON.
